(57) **CLAIM**

I claim the ornamental design for a couples massager, as shown and described.

DESCRIPTION

FIG. 1 is a first perspective view of a couples massager.

FIG. 2 is a second perspective view of the couples massager.

FIG. 3 is a top view of the couples massager.

FIG. 4 is a bottom view of the couples massager.

FIGS. 5 and 6 are right and left side views, respectively, of the couples massager.

FIG. 7 is a rear view of the couples massager; and,

FIG. 8 is a front view of the couples massager.

The broken lines are directed to environment and are for illustrative purposes only; the broken lines form no part of the claimed design.
